ELASTIC STRAP AND PROCESS OF MAKING SAME.

Application filed December 13, 1927. Serial No. 239,643.

While it is desirable to provide a degree of elasticity for shoulder straps for lingerie, elastic suspenders must necessarily be substantially thicker and heavier than non-
5 elastic suspenders. Thin and light straps are, however, very much preferred, and wearers are willing to sacrifice elasticity to lightness. For this reason, such straps are commonly made inelastic.

10 The object of my invention is to provide a lingerie shoulder strap which will respond to the requirements of thinness and lightness and at the same time possess the desired degree of elasticity.

15 I accomplish this object by making a woven material for such shoulder straps which is inelastic throughout the greater part of its length and elastic for the smaller part of its length. The elastic section and 20 the non-elastic section are integral one with another. This result is accomplished by weaving a known fabric of non-elastic threads and in addition thereto providing a series of elastic warp threads (preferably 25 of rubber) which are bound in by the filler throughout that part of the fabric which it is desired to make elastic and which float free of the filler throughout the remainder of the fabric; the floating rubber strands 30 being cut out of the fabric after the weaving is completed. During the weaving operation, the rubber strands are under a tension which increases their length substantially beyond the normal, the elastic section 35 of the finished web shrinking in length as soon as the pull thereon is relaxed.

In the embodiment of the invention here shown, a part of the inelastic section of web adjacent the elastic section of web is woven 40 to form a pocket within which the ends of the rubber strands are confined and concealed.

The invention may be embodied in a variety of different weaves.

45 Fig. 1 is a plan view of a length of web embodying my invention.

Fig. 2 is an enlarged plan view, somewhat diagrammatic, showing one form of weave.

The warp is composed of cotton threads 50 *a* and rubber strands *c*.

In the inelastic part *x* of the fabric, the cotton threads *a* are bound in by the filler threads *b* in a plain one and one weave.

The rubber strands *c*, which are under a pulling strain which elongates them to about 55 twice their normal length, float over all the filler threads. This part *x* of the fabric may be (say) 27 or 28 inches in length.

In the inelastic part *y* of the fabric, the warp threads and filler threads are so interlaced as to form two webs, one above the other, united only along their longitudinal edges, thereby forming a tubular web; the method of weaving which is well known in the art. In Fig. 2, I have shown the threads 60 of the underlying web shaded and the threads of the overlying web unshaded. The rubber strands *c* float between these two webs. The part *y* of the fabric may be (say) half an inch in length. 70

In the elastic part *z* of the fabric, the rubber strands *c* are woven with the filler threads in a plain one and one weave. There are, preferably, two picks of weft *b* to each change in the shed of cotton warp threads, 75 making a two and one weave in this part of the web. This part of the fabric may be woven to a length of (say) four inches.

The long floating rubber strands *c* are cut out of the fabric, while it is under tension, 80 at about the line *w*—*w*, near that end of flat section *x* adjoining tubular section *y*. When the tension on the web is relaxed, section *z* instantly shrinks to (say) half its extended length, and the free ends of rubber extending beyond section *z* through tubular sections *y* shrink to (say) half their extended length, causing them to lie entirely within the tubular section *y*. 85

The finished web thus has an integral 90 elastic section which may be readily elongated but which will resume its natural length when not under strain.

In cutting this web into lengths suitable for individual shoulder straps, it is desirable to have the elastic sections *z* relatively near one end thereof, so that it does not rest over the shoulders. Straps of this character give readily in the movements of the body and constitute a substantial improvement over straps of uniform character—elastic or inelastic—throughout their length. 95

In referring to certain threads as inelastic, I do not mean to imply that they are necessarily absolutely devoid of all elasticity, 100 105 but that they are inelastic relatively to the

elastic threads, which must possess elasticity in a pronounced degree in order to accomplish the purposes of my invention.

What is claimed is:—

- 5 1. The process of making an elastic strap including providing a series of inelastic warp threads and a series of elastic warp threads, interweaving filler threads with both the elastic and inelastic warp threads throughout one part of the length of the warp threads while the elastic warp threads are elongated by tension, interweaving filler threads with only the inelastic warp threads throughout a second part of the length of 10 the warp threads to form a tubular section enclosing the elastic warp threads, interweaving filler threads with only the inelastic warp threads throughout a third part of 15 the length of the warp threads adjacent the said second part to form a flat inelastic section outside of which the elastic warp threads float, and severing the floating portions of the elastic warp threads adjacent the tubular section so that, upon release of 20 tension, the extremities of the elastic warp threads will recede within said tubular section. 25
2. The process of making straps which comprises providing a series of inelastic warp threads and a series of elastic warp threads,

interweaving filler threads with elastic warp threads throughout only a part of the length of the web while said warp threads are under tension, interweaving filler threads with inelastic warp threads throughout the length 35 of the web, the inelastic warp and the filler being so interwoven as to form tubular sections enclosing the elastic warp threads at opposite ends of the first named length of the web, and flat sections beyond the tubular 40 sections and along which the elastic warp threads float, and severing the elastic warp threads at a point so close to the junction of the flat inelastic web section with the tubular inelastic web section that, upon release 45 of tension, the extremities of the elastic warp threads will recede into the tubular section and be thereby confined.

3. A strap including an elastic portion having elastic warp threads therein, an inelastic tubular portion adjacent said elastic portion housing the ends of the said elastic warp threads, and a flat inelastic portion devoid of elastic warp threads adjacent to 50 said tubular portion.

In testimony of which invention, I have hereunto set my hand, at Philadelphia, Pennsylvania, on this 8th day of December, 1927.

MAX N. AARON
